[57] CLAIM

The ornamental design for a wall mount hair dryer or similar article, as shown and described.

DESCRIPTION

FIG. 1 is a front elevational view of a wall mount hairdryer showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a front elevational view of a modified embodiment;

FIG. 8 is a left side elevational view thereof; and

FIG. 9 is a right side elevational view thereof.

The hose portion is shown partially broken away in FIGS. 2, 3, 8 and 9 for ease of illustration.
